UNITED STATES PATENT OFFICE.

JOHN HAPPE, OF BROOKLYN, NEW YORK.

QUILTING-MACHINE.

SPECIFICATION forming part of Letters Patent No. 349,090, dated September 14, 1886.

Application filed January 19, 1881. Serial No. 24,298. (No model.)

To all whom it may concern:

Be it known that I, JOHN HAPPE, of Brooklyn, in the county of Kings and State of New York, United States of America, have invented certain new and useful Improvements in Quilting-Machines, of which the following is a specification.

This invention relates to quilting-machines for the ornamental stitching of quilts, skirts, 10 cloak-linings, and similar work.

The object of the invention is to provide a machine in which curved lines of stitching may be produced with accuracy and dispatch, and in which various ornamental figures, involving either curved or straight lines of stitching, or both, may be produced at one 15 passage of the article to be stitched through the machine, whereby great rapidity and economy are secured in the production of this kind of work.

In the accompanying drawings, which show a convenient arrangement of parts for carrying out the object of this invention, Figure 1 represents a side elevation of this improved 20 quilting-machine, partly in vertical transverse section. Fig. 2 is a plan thereof, with a segment of the outer feed-ring broken away. Fig. 2^a is a central vertical section of the machine on an enlarged scale, showing the horizontal rotary fabric-feeding device in a modified form. Fig. 3 is a detailed sectional end elevation of one of the supporting radial frames or standards and a segment of the fabric-feeding device supported thereon, showing 25 the mechanism for imparting vertical reciprocating motion to the needles of one of the sewing-machines. Fig. 4 is a detail vertical transverse section on line *xx* of Fig. 1, showing the shuttle-actuating mechanism for one 30 of the sewing-machines. Fig. 4^a is a detail vertical transverse section through one of the needle-plates and shuttle-carriers. Fig. 5 is a top view of the cam, which constitutes a part of the mechanism for imparting a horizontal reciprocating motion to one of the 35 sewing-machines. Fig. 6 is a detail top plan of the mechanism for imparting horizontal reciprocating motion to one of the sewing-machines. Fig. 7 is a detail end elevation of 40 mechanism for imparting intermittent rotary motion to the horizontal rotary fabric-feeding

device. Fig. 8 is a side elevation, partly in section on line *yy*, Fig. 2, of one of the sewing-machines adapted to be adjusted obliquely to the radius of the horizontal rotary fabric-feeding device. Fig. 9 is a detail view of ornamental wave-strokes produced on this machine. Fig. 10 is a top view of the horizontal rotary fabric-feeding device provided with pattern-cams for controlling the reciprocating movements of the sewing-machines.

Similar letters of reference indicate corresponding parts in the different figures.

A A in the drawings represent a number of upright frames, which are arranged in a circle 45 radially to a common center and secured to the floor or foundation. These radially-arranged frames are provided at their inner ends toward the center and at their outer ends at the circumference of the circle with horizontal yoke-shaped arms A', arranged at right angles, or nearly so, to the frames. The arms A' support in bearings at their opposite ends anti friction rollers *a*, the axes of which are radial to said circle. The outer ends of the rollers *a* and 50 the inner ends of the rollers *a'* are provided with flanges. A horizontal rotary quilting-frame or fabric supporting and feeding device is supported upon and adapted to rotate on said anti-friction rollers. This horizontal rotary quilting-frame may consist of a single ring, B, as shown in Fig. 2^a, to the circumference of which the material or article to be quilted is held by means of pins or otherwise, in the usual manner of holding articles to quilting- 55 frames; or it may consist of the ring B in connection with a smaller ring, B', arranged concentric thereto, as shown in Figs. 1 and 2, one edge of the fabric to be quilted being attached to one ring and the opposite edge there- 60 of to the other ring. The ring B is supported on the outer series of rollers, *a*, in the yoke-shaped arms A', and the smaller ring, B', is supported on the inner series of rollers, *a'*. The flanges on said rollers serve to keep the 65 rings in place. When the ring B' is not used, the rollers *a'* may be dispensed with. These rings are provided with cogs or teeth, whereby they are engaged by pinions for rotating them, which teeth are preferably countersunk in the 70 under side of the rings, so as not to project below the level thereof, as in that case they

might interfere with the smooth motion of the rings over the rollers.

If desired, the horizontal rotary quilting-frame may be composed of segments of the rings B B', including approximately a sector-shaped space, in which case a suitable reversing mechanism will be employed for returning the frame to its starting-point after it has passed through an arc of a circle and carried the work stretched upon it through one or more of the sewing-machines adapted to operate thereon.

The feed-rings B B' receive intermittent horizontal rotary motion around their common center by a suitable actuating mechanism, which, as shown, consists of an inclined shaft, b, supported in bearings on one of the frames A, and provided with a smaller pinion, b', at its inner end, and a larger pinion, b'', near its outer end, said pinions working, respectively, with the circumferential racks of the inner and outer feed-rings. Intermittent rotary motion is imparted to the shaft b by means of an adjustable pawl-and-ratchet mechanism, which is supported on a bracket of one of the frames A, and comprises a ratchet-wheel, d', at the outer end of the shaft b, a pawl, d'', pivoted to the upper end of an oscillatory lever, d, and operated by a link, d'', connecting it with a crank-wheel, d', on the outer end of a horizontal shaft, d''. The lever d is provided with a series of holes or pins, with either one of which the link d'' may be connected to regulate the stroke of the lever d and the degree of motion of the fabric-feeding device at each step. The horizontal shaft d'' turns in bearings of the yoke A' of said frame, and is provided at its inner end with a pinion, which meshes with a crown-wheel, d'', on the central vertical driving-shaft, C. The skirts, quilts, or other work secured to the quilting-frame is thus fed in a circular horizontal direction intermittently to a series of organized sewing-machines, D D, which are supported and guided in the radial frames A, each of said machines being mounted on a carriage, D', to which radial reciprocatory motion is imparted from the central driving-shaft, C, by a suitable transmitting mechanism. The transmitting mechanism shown consists of a gear-wheel, e, and pinion e', cam e'', connecting-rod e'', adjustable spring-pawl and ratchet-wheel e' e'', and a vertical shaft, e'', the latter having a grooved horizontal cam, e'', at its upper end, as shown clearly in Figs. 1, 5, and 6. The grooved cam e'' engages a pin, e'', at the under side of the sewing-machine carriage D', which receives its proper laterally-reciprocating motion by the eccentricity of the cam-track and the adjustable spring-pawl e'', according to the special ornamental figure to be stitched by each sewing-machine D.

To the sewing-machine carriage D' are pivoted the arms f of the shuttle-drivers f', which arms are oscillated by cams f'', keyed to a radial shaft, f'', that is revolved by an end pinion, f'', and the center crown-wheel, d'', said

pinion being of sufficient length to remain in mesh with the crown-wheel d'' while following the laterally-reciprocating motion of the sewing-machine carriage D'. The radial shaft f'' turns in bearings of the sewing-machine carriage D', and is furthermore guided in fixed sleeves of the standard A while following the laterally-reciprocating motion of the carriage D'. The oscillating arms f are slotted at their upper ends, so as to provide the required play for the connecting-pins of the shuttle-drivers, the arms being kept in contact with the cams by spiral springs f'', as shown clearly in Fig. 4. The shuttle-drivers f' are guided in grooves below the shuttle-races, which are formed of a fixed top plate, g, attached to the underside of the needle-plate, and a downwardly-moving bottom plate, g', which is guided on fixed downwardly-extending rods g' of the top plate and supported upon cushioning-springs g'' of the same.

The object of the movable bottom plate, g', is to facilitate the removal of any shuttles for supplying them with thread or replacing them by simply lowering the bottom plate sufficiently to get at the shuttles, in which case the pins of the shuttle-drivers f' move in the slots of the oscillating arms f.

Several shuttles may be arranged in the same race, one back of the other, as shown in Figs. 4 and 4', according as the machine is made with two or more rows or gangs of needles, in which case the shuttle driver has forked arms.

Each sewing-machine D is arranged with one or more gangs of needles, which are attached to one or more needle-bars, to which vertically-reciprocating motion is imparted by means of a grooved cam, h, at the outer end of the radial shaft f''. The grooved cam h engages a fixed pin, h', of one of the vertical guide-rods h'' of the needle bar or bars, said guide-rods sliding in holes of bracket-arms h'' of the sewing-machine carriage D'. The arms h'' extend beyond the outer feed-ring, B, so as to clear the same entirely. The pressure-feet h' are made of spring-steel and applied to a horizontal rod, h'', parallel to and below the needle-bar, and are pressed down upon the fabric by fixed pins h'' of the needle-bar, which pass through holes of the supporting-rod of the spring-presser on the descent of the needle-bar, as shown in Figs. 1 and 2. The several sewing-machines are arranged at different points more or less distant from the common center, and each is intended to produce a certain specific figure, design, or part thereof upon the quilt, skirt, or other material.

An entire quilt or one or more skirts may be stitched in a variety of ornamental stitching by one rotation of the feed ring or rings, whereby the article or articles are passed successively through the different sewing-machines, one sewing-machine performing diagonal stitching, another parallel wave-lines, a third diamonds, a fourth circular stitching,

&c. If the work of either one of the machines is not desired on the quilt or skirt, the entire sewing-machine carriage is thrown out of gear with its transmitting mechanism, so as to be 5 at rest without performing any work. By inserting other pattern-cams and other needle-bars having the needles arranged at different distances apart the designs may be varied as desired.

10 When the machine is used for stitching quilts or cloak-linings, the inner circular feed-ring, B', is preferably dispensed with and a central disk, C', substituted, said disk turning loosely in suitable bearings of the central 15 driving-shaft and following the motion of the outer feed-ring. In this case the center or inner edge of the work is pinned to the disk C', while the outer edge is secured to the ring B. For stitching skirts, the interior feed-ring, 20 B', is used, in which case as many skirts as can be stretched between the rings are secured thereto.

For the purpose of producing very close and intersecting lines of ornamental stitches, one 25 or more of the sewing-machines are not placed radially to the feed-rings, but are arranged to swing around a vertical swiveled shaft, so as to be capable of adjustment through an angle of ninety degrees to the radius of the feed- 30 rings. In Figs. 2 and 8 such an adjustable sewing machine is shown, the carriage of which is made to swing around a vertical shaft, i, which is swiveled at its lower end and supported below the swiveled portion on a suitable step-bearing, and at the upper end in a curved bearing of the sewing-machine carriage, the vertical shaft serving, also, for transmitting reciprocating motion to the sewing-machine carriage from the central driving- 40 shaft by means of a crown-wheel and pinion, horizontal shaft, a set of bevel-gears, i', at the lower end, and a set of bevel-gears, i'', at the upper end of the swiveled shaft i. The upper bevel-wheels impart revolving motion to a 45 horizontal shaft, i³, (corresponding to the shaft f³ of the non-swiveling machines,) which carries the shuttle-driving cams, and at its outer end a grooved cam, h, by which vertically-reciprocating motion is imparted to the needle bar or bars above the fabric, in the same manner as in the vertically-arranged sewing-machines. The swiveled transmitting-shaft is enabled to follow the laterally-reciprocating motion of the sewing-machine carriage, which is imparted by an interchangeable pattern, l, attached to the circumference of the outer feed-ring, as shown in Figs. 2 and 8. The pattern l bears upon an anti-friction roller, l', of the sewing-machine carriage, 55 which latter is held in contact with the pattern by a spiral spring, l'', at the opposite end of the carriage D', as shown in Fig. 8.

The sewing-machine D may be readily adjusted through an angle of nearly ninety degrees to the radius of the feed-rings drawn through shaft i by swinging its carriage around said shaft. For this purpose, as well as for

admitting the reciprocating motion of the carriage in every position in which it is placed, it is supported on ball-shaped anti-friction 70 rollers i', which are retained between concentric flanges of a platform, i⁵, which is attached centrally to the upright standard A of the sewing-machine, as shown in Fig. 8. The platform i⁵ has a central opening wide enough 75 to admit the oscillating motion of the swiveled shaft in following the motion of the sewing-machine carriage, the upper bearing of the shaft having an inner convex face to admit of this motion. According to the greater 80 or less inclination of the sewing-machine to the radius of the feed-rings passing through the swiveled shaft, the stitches may be run more or less close to each other, which could not otherwise be accomplished, as the shuttles 85 could not be placed so close to each other. In this case, however, the shuttles have full play, while the stitches are run close to each other by the oblique position of the machine. Irregular work of all kinds may be produced, 90 according to the shape of the pattern-frame. By employing one or two sewing-machines which can be set into oblique positions, the range of the work accomplished by my improved machine is extended, and thereby almost 95 every desired ornamental configuration of stitches obtained. In this connection I may also state that the laterally-reciprocating motion may be imparted to the sewing-machine carriages by means of pattern-cams of 100 suitable shapes, which are secured to the circumference of the outer feed-ring, said pattern-cams engaging anti-friction rollers of the carriages.

In case it is desired to produce an oval, oblong, or other pattern on the quilt, in place of the circular one, I attach to the outer feed-ring an extension pattern-frame of oval, oblong, or other shape, as shown in Fig. 10. This extension-frame may have an undulating 110 or other irregular outline, by which the sewing-machines, or those of them designed to be operated by this frame, are correspondingly moved so as to reproduce the pattern of the extension-frame throughout the quilt or other 115 fabric. My improved machine is thus not confined to circular work only, but also adapted for work of other shapes by the addition of differently-shaped extension-patterns to the outer feed-ring.

120 What I claim as my invention is—

1. In a quilting-machine, the combination, substantially as set forth, of a horizontal rotary fabric supporting and feeding device adapted to feed the fabric in a circle or arc of 125 a circle and a horizontally-reciprocating sewing-machine arranged to operate within the circle traversed by said rotary fabric-feeding device.

2. In a quilting-machine, the combination, substantially as set forth, of a horizontal rotary fabric supporting and feeding device adapted to feed the fabric in a circle or arc of 130 a circle and a horizontally reciprocating and

swiveling sewing-machine arranged to operate within the circle traversed by said rotary fabric-feeding device.

3. In a quilting-machine, the combination, substantially as set forth, of a horizontal rotary fabric-feeding device adapted to feed the fabric in a circle or arc of a circle and provided with a pattern-cam, a horizontally-reciprocating sewing-machine arranged to operate within the circle traversed by said rotary fabric-feeding device, and means for holding said machine in contact with said cam.

4. In a quilting-machine, the combination, substantially as set forth, of a horizontal rotary fabric supporting and feeding device adapted to feed the fabric in a circle or arc of a circle, organized sewing-machines arranged to converge toward each other within the circle traversed by said fabric supporting and feeding device, and means for imparting an intermittent step-by-step motion to said device.

5. In a quilting-machine, the combination, substantially as set forth, with a horizontal rotary fabric supporting and feeding device consisting of two concentric feed-rings, of a sewing-machine arranged to operate within the circle traversed by said rotary fabric-feeding device.

6. In a quilting-machine, the combination, substantially as set forth, of radially-arranged supporting-frames having flanged guide-rollers, a horizontal rotary fabric supporting and feeding device supported on said rollers, and a sewing-machine arranged to operate within the circle traversed by said rotary fabric-feeding device.

7. In a quilting-machine, the combination, substantially as set forth, with an intermittently-moving horizontal rotary fabric supporting and feeding device, of a reciprocating sewing-machine arranged to operate within the circle traversed by said rotary fabric-feeding device, the carriage of which is adapted to swing around a vertical swiveled shaft, and supported on a flanged circular platform, and spherical anti-friction rollers, whereby it is adapted to be set at an oblique angle to the radius of the feeding device.

8. In a quilting-machine, the combination, substantially as set forth, of an intermittently-moving horizontal rotary fabric supporting and feeding device provided on its periphery with a pattern-cam, a sewing-machine arranged to operate within the circle traversed by said rotary fabric-feeding device, the carriage of which is actuated by the pattern-cam, and a spring for keeping said carriage in contact with said pattern-cam.

9. In a quilting-machine, the combination, substantially as set forth, of two concentric feed-rings provided with cogs and a radial shaft having pinions of different sizes engaging the cogs of the inner and outer feed-rings, whereby a harmonious feed motion is imparted to said rings.

10. In a quilting-machine, the combination of a horizontal rotary fabric supporting and

feeding device, a vertical shaft, a gear-wheel attached to said shaft, a crown-wheel attached to said shaft, a series of radial shafts provided at their inner ends with pinions which mesh with said crown-wheel and at their outer ends with cam-disks, vertically-reciprocating needle-carrying arms actuated by said cam-disks, horizontally-reciprocating sewing-machine carriages, and mechanisms connecting said carriages with said gear-wheel, substantially as set forth.

11. In a quilting-machine, the combination of a horizontal rotary fabric supporting and feeding device, a vertical shaft, a gear-wheel attached to said shaft, a crown-wheel attached to said shaft, a series of radial shafts provided at their inner ends with pinions which mesh with said crown-wheel and at their outer ends with cam-disks, vertically-reciprocating needle-carrying arms actuated by said cam-disks, horizontally-reciprocating sewing-machine carriages, mechanisms connecting said carriages with said gear-wheel, and mechanism connecting said crown-wheel with said horizontal rotary fabric-feeding device for actuating the latter, substantially as set forth.

12. The combination, in a quilting-machine, of a horizontal rotary fabric-feeding toothed ring, a horizontally-reciprocating sewing-machine arranged to operate within the circle traversed by said feeding-ring, a pinion meshing with said toothed ring, and a ratchet mechanism for actuating the shaft of said pinion intermittently, substantially as described.

13. The combination, in a quilting-machine, of a horizontal rotary fabric-feeding toothed ring, a horizontally-reciprocating sewing-machine arranged to operate within the circle traversed by said feeding-ring, a gear meshing with said feeding-ring, and a ratchet mechanism for actuating the shaft of said gear intermittently, said ratchet mechanism being adjustable, whereby the step-by-step motion of the feeding-ring is regulated, substantially as described.

14. The combination, in a quilting-machine, of a horizontal rotary fabric feeding and supporting device, a horizontally-reciprocating sewing-machine arranged to operate within the circle traversed by said rotary fabric-feeding device, and mechanism for reciprocating said sewing-machine intermittently, consisting of a cam engaged by a pin of the sewing-machine carriage and ratchet mechanism for intermittently actuating the shaft of said cam, substantially as described.

15. The combination, in a quilting-machine, of a horizontal rotary fabric supporting and feeding device, a horizontally-reciprocating sewing-machine arranged to operate within the circle traversed by said rotary fabric-feeding device, and mechanism for reciprocating said sewing-machine intermittently, consisting of a cam engaged by a pin of the sewing-machine carriage and ratchet mechanism for intermittently actuating the shaft of said cam, said ratchet mechanism being adjustable,

whereby the steps of the sewing-machine carriage are regulated, substantially as set forth.

16. In a quilting-machine, the combination of a horizontal rotary fabric supporting and feeding device, a ratchet mechanism for imparting an intermittent motion thereto, a horizontally-reciprocating sewing-machine arranged to operate within the circle traversed by said fabric-feeding device, and a ratchet mechanism for intermittently moving said sewing-machine horizontally, substantially as set forth.

17. In a quilting-machine, the combination of a horizontal rotary fabric supporting and feeding device, a ratchet mechanism for imparting an intermittent motion thereto, a horizontally-reciprocating sewing-machine arranged to operate within the circle traversed by said fabric-feeding device, and a ratchet mechanism for intermittently moving said sewing-machine horizontally, substantially as set forth, whereby the horizontal step-by-step motions of said feeding device and said sewing-machine are regulated, substantially as described.

18. In a quilting-machine, the combination, with a sewing-machine and a fabric-carrier, upon which a fabric may be held extended and rotated between the upper and lower arms of a sewing-machine, of movable supports permitting the bodily movement of one of said parts in a direction transverse to the line of rotation of the carrier, whereby the lines of stitching will be formed in various positions on the extended fabric, substantially as herein described.

19. In a quilting-machine, the combination, with a sewing-machine and a fabric-carrier, upon which a fabric may be held extended and rotated between the upper and lower arms of the sewing-machine, of movable supports for the sewing-machine, permitting its bodily movement in a direction transverse to the line of rotation of the carrier, whereby the lines of stitching will be formed in various positions on the extended fabric, substantially as herein described.

20. In a quilting-machine, the combination, with a sewing-machine, of a rotary fabric carrier, on which the fabric may be stretched or extended in a plane perpendicular to the needle, and the axis of which is parallel with the needle, and supports for said carrier which permit its rotation between the arms of the sewing-machine, substantially as herein described.

21. In a quilting-machine, the combination, with a sewing-machine, of a rotary fabric-carrier, on which a fabric may be stretched or extended in a plane perpendicular to the needle, and the axis of which is parallel with the

needle, and a supporting-track, on which the carrier may turn on its axis and between the arms of the sewing-machine, substantially as herein described.

65

22. In a quilting-machine, the combination, with a sewing-machine and fabric-supports, of a rotary carriage for one of said parts having its axis parallel with the needle, and supports which permit the rotation of said carriage in a plane perpendicular to the needle, to change the relative position of the needle and fabric, substantially as herein described.

70

23. In a quilting-machine, the combination, with a sewing-machine and a rotary fabric-carrier, on which a fabric may be stretched or extended in a plane perpendicular to the needle, and the axis of which is parallel with the said needle, of supports for one of said parts movable to vary the distance between the axis of the fabric-carrier and the needle, substantially as herein described.

75

24. In a quilting-machine, the combination, with a sewing-machine and a rotary fabric-carrier, on which a fabric may be stretched or extended in a plane perpendicular to the needle, and the axis of which is parallel with said needle, of supports for the sewing-machine movable to carry the needle toward and from the axis of the fabric carrier, substantially as herein described.

80

25. In a quilting-machine, the combination, with a sewing-machine and a rotary fabric-carrier, on which a fabric may be stretched or extended in a plane perpendicular to the needle, and the axis of which is parallel with the said needle, of a carriage for supporting one of said parts, supports on which said carriage may be moved transversely to vary the distance between the axis of the fabric-carrier and needle, and pattern mechanism for controlling the transverse movement of such carriage, substantially as herein described.

90

26. In a quilting-machine, the combination, with a sewing-machine and a rotary fabric-carrier, on which a fabric may be stretched or extended in a plane perpendicular to the needle, and the axis of which is parallel with said needle, of a carriage for the sewing-machine movable in a transverse direction, to carry the needle toward and from the axis of the fabric-carrier, and pattern mechanism for controlling the movements of the sewing-machine carriage, substantially as herein described.

100

In testimony that I claim the foregoing as my invention I have signed my name, in presence of two witnesses, this 10th day of January, 1881.

110
